UNITED STATES PATENT OFFICE

149,680

DESIGN FOR A BRASSIÈRE

William Rosenthal, Bayville, N. Y., assignor to
Maiden Form Brassiere Company, Inc., New
York, N. Y., a corporation of New York

Application August 10, 1945, Serial No. 121,359

Term of patent 14 years

(Cl. D20—4)

To all whom it may concern:

Be it known that I, William Rosenthal, a citizen of the United States, residing in Bayville, county of Nassau, and State of New York, have invented a new, original, and ornamental Design for a Brassière, of which the following is a specification, reference being had to the accompanying drawings, forming part thereof.

Figure 1 is a front perspective view of a brassière showing my new design; and

Figure 2 is a rear perspective view of the brassière shown in Figure 1.

I claim:

The ornamental design for a brassière, as shown.

WILLIAM ROSENTHAL.
